Patented Mar. 26, 1968

210,588

COMPUTER CONTROL CABINET OR SIMILAR ARTICLE

Charles N. Mazza, Framingham, Mass., assignor to
Honeywell Inc., Minneapolis, Minn., a corpora-
tion of Delaware

Filed Dec. 16, 1966, Ser. No. 5,063

Term of patent 14 years

(Cl. D26—5)

Fig. 1

Fig. 4

Fig. 3

Fig. 2

Fig. 5

FIGURE 1 is a perspective view taken from the top, front and one side of a computer control cabinet or similar article embodying the new design;

FIGURE 2 is a rear elevational view thereof;

FIGURE 3 is a front elevational view thereof;

FIGURE 4 is an elevational view taken from the other side thereof; and

FIGURE 5 is a top plan view thereof.

The dominant features of the claimed design reside in the portions shown in solid lines in the figures of the drawing.

What is claimed is:

The ornamental design for a computer control cabinet or similar article, substantially as shown and described.
